UNITED STATES PATENT OFFICE.

LEWIS F. WOOD, OF BROOKLYN, NEW YORK.

DOUBLE-ACTING LOCK FOR AUTOTRUCK CABS

Application filed June 2, 1925. Serial No. 34,409.

This invention relates to the art of locks and latches, and has particular reference to a fastener of the latch type for sliding doors.

Among the objects of my invention may be noted the following: to provide a double-acting fastener or latch for sliding doors, which will operate to hold the door open and also hold the door closed; to provide a combination of means, parts and devices specially adapted to hold the sliding door of an auto-truck cab in either an open or closed position; to provide means for holding the sliding door of an auto-truck cab in either an open or a closed position, coupled with means for readily shifting the holding means from either the inside or outside of the cab, so that, if the door be fastened open or fastened closed, the operator can readily manipulate the holding means to release the door; to provide a combination of means whereby the sliding door of an auto-truck cab may be prevented from sliding or shifting its position when open, and also held securely when closed regardless of the angle or inclination of the cab with reference to the traction surface of the truck; and to provide a combination of simple and effective means, for bringing about the foregoing purposes, which are readily adapted to the sliding door and door-frame of an auto-truck cab, and which are strong, durable and economical to produce.

With the foregoing objects in view and others which will be detailed during the course of this description, my invention consists in the parts, features, elements and combinations thereof hereinafter described and claimed.

40 In order that my invention may be clearly understood, I have provided drawings wherein:

Figure 1 is a side elevation of a portion of an auto-truck cab provided with a sliding door and having certain parts broken away, in order to disclose details of construction within the scope of my invention;

Figure 2 is a view showing a portion of the inside of the cab, the sliding door being held closed by the structure of my invention;

Figure 3 is a view in section substantially on the line 3—3 of Figure 2, the arrows indicating the direction of sight, it being noted that the door is latched closed;

55 Figure 4 is a view similar to Figure 3,

but showing the door latched in an open position;

Figure 5 is a view in side elevation, parts being broken away, of the latch and latch frame embodying my invention, this figure 60 being on a commercial scale;

Figure 6 is a view looking at the front edge of Figure 5, the figure being broken away on account of limitations of the sheet;

Figure 7 is a perspective view of the catch part or keeper for holding the door in closed position; 65

Figure 8 is a perspective view of the catch part or keeper for holding the door in open position; and

Figure 9 is a perspective view of the duplex latch which cooperates with either of the catch parts of Figures 7 and 8.

Referring to the drawings, the numeral 1 indicates the frame or body of the cap of an auto-truck, 2 the sliding door, 3 the frame or casing which supports the latch 4, which latter is adapted to engage the angular catch-plate or keeper 5 applied to the edge of the door frame or opening at the back of the latter, and also adapted to engage the angular catch-plate or keeper 6 applied to the edge of the door frame or opening at the front of the latter. The

opening at the front of the latter. The frame or casing 3 is sunk within an opening 85 at the front edge of the sliding door so as to be flush all around with the surfaces of the door material, so that the latch 4 may protrude or extend beyond the front edge of the door and within the cab so as to be manipulated, under certain circumstances 90 from within the cab by the driver. The details of construction are clearly shown in the enlarged views of Figures 5 to 9, inclusive. 95

Referring to Figure 5, the frame or casing 3 is made up of a plurality of parts firmly held together in any suitable way and having a form to provide a chamber 7, an edge plate 8 having an opening 9 through which the latch 4 projects, said latch being journaled in the opposite sides of the casing, within the chamber 7, by means of barrel 10, provided with an angular opening 11, for the stem 12, of the handle 13, by which the barrel may be turned. The barrel is rigidly secured within the enlargement 14 of the latch, so that the latch may be shifted by the handle when desired. The latch 4 is normally depressed and held in engagement

with the lip 15 at the bottom of the opening 9 of the edge plate 8, by means of a U-shaped spring having a coil 16, and the upper leg 17 of which engages the top of the chamber 7 and the lower leg 18 of which engages the top of the latch within the chamber.

The body of the latch is U-shaped and has one of its legs longer than the other, the 10 longer leg carrying the barrel 10, as previously described, and also having near its bend a wedge-shaped lifting lug 19 adapted to ride on and snap behind the lip 20 at the base of the angular opening 21 of the catch- 15 plate or keeper 6, applied to the front of the door frame. The latch 4 is also provided with a second wedge-shaped lifting lug 22 at the extremity of its shorter leg, said lug being adapted to ride upon and snap over the 20 lip 23 at the base of the opening 24 of the catch-plate or keeper 5 applied to the rear of the door frame. The two catch-plates or keepers 5 and 6 are right-angular in form and may be of any size in comparison with 25 the frame or casing 3; but, I prefer to make the two catch-plates of approximately the length of the frame 3. However, the said plates 5 and 6 will be made of a size adapted to embrace the angular portion of the 30 door frame at the front and rear thereof, consideration being given to strength, stability and solidity according to the characteristics of the cab body. The catch-plate 6, at the base of its angular opening 21 is 35 provided with a horizontal ledge 25 extending inwardly to a position just short of where the lug 19 will rest when the latch 4 is cooperatively engaged with the catch-plate 6, as shown in Figures 2 and 3. Below the 40 ledge 25 is a beveled or inclined surface 26 emerging in the surface of the wall of the plate 6, the same being adapted to permit the insertion of the finger of the operator below the latch 4, when in the position of Figure 45, to raise the latch and release it from the catch-lip 20, when it is desired to open the door, this being readily effected from the inside of the cab and the seat of the operator. When the door 2 is shifted to the left, 50 viewing Figure 3, the lug 22, upon reaching the catch-plate 5, will slide upon and snap over the lip 23, thus locking the door 2 in open position, as shown in Figure 4. Under these conditions, the operator can lift 55 the latch from the outside of the cab by manipulating the handle 13, which is also true when the door is latched closed, as in Figures 1, 2 and 3.

Viewing Figures 3, 4, 5 and 9 particularly, 60 it will be seen that the latch is pivoted at one extremity, or at the inner end of its longer leg, and may be easily manipulated from its opposite extremity or at its bend, this giving a long leverage enabling the operator to readily lift the latch from the interior of the

cab when the door is closed, as shown in Figures 1 to 3, inclusive. It will also be understood that my duplex, double acting latch is capable of being raised or lifted in four ways, viz, by the handle at its fulcrum, by the finger of the operator at its bend, by the lug 19 in cooperation with the lip 20, and by the lug 22 in cooperation with the lip 23.

The many advantages and valuable commercial features of my duplex latch need not be enlarged upon here, as they will be readily apparent to users of the same and those skilled in the art.

Having thus described my invention, what I claim and desire to secure by Letters Patent is:

1. In combination with a pivotally mounted latch U-shaped in form, a catch-plate having an angular opening adapted to receive the closed end of the latch, and a latch-lug on one arm of the latch adapted to engage the catch-plate when the closed end of the latch enters said opening.

2. In combination, a U-shaped latch pivoted at the end of one of its arms and having a catch-lug on the extremity of its other arm, and a catch-plate having an opening adapted to receive said catch-lug so that it may engage the edge of the plate at the bottom of said opening.

3. In combination with the door of an auto cab, a latch-frame secured thereto, a latch pivotally mounted in the frame and protruding through one side thereof, a keeper secured to the edge of the door opening at the back of the latter, a keeper secured to the edge of the door opening at the front of the latter, and depending plugs carried by the protruding portion of the latch for cooperation with the two keepers, whereby the door may be fastened in both an open and a closed position.

4. In combination with the sliding door of an auto cab, a U-shaped duplex latch protruding from one edge of the door and comprising means for latching the door when closed and means for unlatching the door when open.

5. In combination with the sliding door of an auto cab, a U-shaped device having depending lugs for latching the door when open and for unlatching the door when closed, catch plates for the lugs one of which has means enabling the latching device to be shifted from the inside of the cab.

6. In combination with the sliding door of an auto cab, a latching means carried by the door at its front edge and protruding therefrom, means carried by the door frame at both the back and front of the door opening for interacting with the latching means, whereby the door may be held by the latch in either opened or closed position, said latching means including a spring-con-

trolled, U-shaped, double acting latch member.

7. In combination with the sliding door of an auto cab, means carried by the cab frame at opposite extremes of travel of the door for holding the latter, and latch means carried by the door and protruding from the edge thereof for cooperation with the said holding means and operating automatically to engage said holding means when the door reaches the two extremities.

8. In combination with the sliding door of an auto cab, an automatically acting duplex latching device carried by said door and protruding from the edge thereof and recurved upon itself in a horizontal plane, and means at the opposite extremities of movement of the door for holding the latter at the opposite extremes by engagement therewith.

9. In combination, a U-shaped latch pivotally supported at the end of one of its arms and having a catch-lug on said arm and a catch-lug on the extremity of its other arm, a catch-plate having an angular opening adapted to receive the closed end of the latch and one of the lugs, and a second catch-plate having an opening adapted to receive the other lug.

10. In combination, a U-shaped latch pivotally supported at the end of one of its arms and having a catch-lug on said arm and a catch-lug on the extremity of its other arm, a catch-plate having an angular opening adapted to receive the closed end of the latch and one of the lugs, said catch-plate having a ledge extending into said opening and a beveled surface extending from the

ledge and merging into the surface of the plate, and a second catch-plate having an opening adapted to receive the other lug on the latch.

11. A lock having a pivotally mounted, spring-controlled U-shaped member, each leg of the member being provided with a depending latch lug.

12. In combination, a casing adapted to be applied to a door, said casing having a chamber and in the latter a pivotally mounted U-shaped latch extending through the casing and having its free end disposed outside the casing, said latch being provided on each of its legs with a depending lug, a catch-plate having an opening adapted to receive the latch and engage one of its lugs, and a second catch-plate having an opening adapted to receive the latch and engage the other lug thereof.

13. A catch-plate right-angular in cross-section having an opening therein adapted to receive a latch, one member of said plate having a catch lip at the base of the opening, and the other member of said plate having a ledge extending into the opening at the base thereof, and a beveled surface extending from the ledge to the surface of the plate.

14. In combination with a pivotally mounted latch U-shaped in form, a catch-plate having an angular opening adapted to receive the closed end of the latch with an arm of the latch overhanging the edge of the opening, said plate being provided with a beveled portion below the arm of the latch adapted to enable the latch to be lifted by pressure thereon.
